UNITED STATES PATENT OFFICE.

MARSHALL SAUCEDO, OF SAN FRANCISCO, CALIFORNIA.

SIDEWALK-BOX COVER.

1,029,719.

Specification of Letters Patent. Patented June 18, 1912.

Application filed August 9, 1911. Serial No. 643,203.

To all whom it may concern:

Be it known that I, MARSHALL SAUCEDO, a citizen of the United States, residing at San Francisco, in the county of San Francisco and State of California, have invented a new and useful Improvement in Sidewalk-Box Covers, of which the following is a specification.

This invention relates to a sidewalk box 10 cover, and the object of the invention is to prevent the removal of the cover from such boxes by children, or by other unauthorized parties.

The invention consists of a cover which 15 can be readily locked in position by means of a key of a particular construction, in combination with a suitably constructed box cover and the said key is presumed to be held in the possession of the adjoining property owner, or to be held by the agent of the 20 corporation owning the water or gas mains to which said boxes lead.

In the accompanying drawings, Figure 1 is a plan view of the device. Fig. 2 is an 25 inverted plan view of the cover. Fig. 3 is a section on the line 3—3 of Fig. 1, showing the position of the key for the purpose of unlocking the cover. Fig. 4 is a similar section showing the position of the key for 30 the purpose of locking the cover.

In these drawings 1 represents the upper portion of the box, which box is provided with a circular removable perforated cover portion 2. It will be understood however 35 that the shape of the cover 2 and the perforations are not essential to the invention, but are merely parts of the preferred form of construction. This cover is provided with a radial slot 3, and also with an oblong 40 slot 4, which is parallel to it and adjacent the opposite side or margin of the cover. These slots are the only portions of the invention which appear upon the outside. The interior of the box carries upon its top a 45 circular flange 5, which flange is cut as shown at 6, said cut portion being in alignment with the adjacent slots 3 and 4 respectively. At the end of the radial slot 3 a lug 7 is formed upon the under face of the 50 cover and engages the adjacent cut out portion 6 of the flange. Upon the opposite side of the cover, and also upon the under face of the cover is a guide way 8, in which slides the body portion of a wedge shaped bolt 9,

the outer end of which is provided with a 55 transverse head 10. This bolt is adapted to pass through the other cut out portion 6 of the flange 5, opposite that portion engaged by the lug 7, and the said bolt and lug together lock the cover in place. The key consists of a suitable handle 11 provided with a curved member 12, a shoulder 13 opposite the point of the hook, and a stop 14 upon the rear curved face of the hook member.

To unlock the cover the hook member is 60 inserted in the slot 4 with the point of the hook bearing upon the head 10 of the bolt and the shoulder bearing upon the cover. The handle is then drawn in the direction 65 of the arrow (Fig. 3) until the stop 14 engages the cover. This will cause the bolt to 70 slide in the guide way 8 a sufficient distance to disengage it from the top of the box withdrawing it from the cut out portion 6 of the flange 4.

To lock the cover in position the key is 75 inserted in the slot 3 and moved in the opposite direction. This causes the bolt to move back along the guide way 8 and through the adjacent cut out portion 6 of 80 the flange 5 and the cover is again locked upon the box.

What I claim is:—

1. The combination with a box, a cover for said box, said cover being provided with 85 two offset slots, a guide way carried by the under side of the cover, a bolt slideable in the guide way and adapted to be moved in one direction to engage a portion of the box, and a key adapted when inserted in one slot 90 to move the bolt in one direction and when inserted in the other slot to move the bolt in the other direction.

2. The combination with a box having a 95 cut out top portion, a cover adapted to close said cut out portion, said cover having slots adjacent its opposite margins, a guide way in alignment with one of said slots, a bolt slideable in said guide way and adapted to engage the under side of the box top, a 100 transverse head carried by the bolt and lying between said slots, and a key adapted to be inserted through said slots to engage respectively opposite sides of said head.

MARSHALL SAUCEDO.
